United States Patent Office

Des. 196,641
Patented Oct. 22, 1963

196,641

DENTAL EQUIPMENT UNIT

Kenneth C. Sharp, 1320 Fieldwood Drive, and Tilmon L. Sharp, 208 Lynnwood Drive, both of Knoxville, Tenn.

Filed May 4, 1962, Ser. No. 69,970

Term of patent 14 years

(Cl. D24—1)

FIGURE 1 is a top plan view of a dental equipment unit embodying our new design;

FIGURE 2 is a front elevation view thereof, the rear not shown is substantially flat and plain; and

FIGURE 3 is a side elevation view thereof, the opposite side is substantially flat and plain.

The dominant features of our design reside in the portions shown in full lines.

We claim:

The ornamental design for a dental equipment unit, as shown and described.
